UNITED STATES PATENT OFFICE.

JOSEPH RABER, OF POPLAR BLUFF, MISSOURI, ASSIGNOR TO DALTON ADDING MACHINE COMPANY, OF ST. LOUIS, MISSOURI, A CORPORATION OF MISSOURI.

ESCAPEMENT FOR TYPE-WRITERS AND RECORDING-MACHINES.

1,005,784.

Specification of Letters Patent. Patented Oct. 10, 1911.

Application filed February 1, 1909. Serial No. 475,403.

To all whom it may concern:

Be it known that I, JOSEPH RABER, a citizen of the United States, residing at Poplar Bluff, Missouri, have invented a new and useful Escapement for Type-Writers and Recording-Machines, of which the following is a specification.

This invention relates to escapements for typewriting and other recording machines wherein a lateral step by step movement is imparted to the paper carriage during the operation of the machine.

In a companion application filed January 18, 1909, Serial No. 472,823, I have described the construction and operation of an improved escapement including the escapement shaft and wheel and adjustable pawls movable across the path of the escapement wheel and adjustable with respect to each other to effect speed or regular escapement on their operation.

The present invention relates to mechanism to be embodied in a machine in combination with the mechanism just referred to, and includes an improved mechanism for controlling the operation of the escapement in its different adjustments, and an improved device for operating said controlling means.

In the accompanying drawings Figure 1 is a perspective view of the escapement embodying my present invention. Fig. 2 is a perspective view of the controlling shaft detached from the remaining portion of the mechanism. Fig. 3 is a perspective view of the tension regulating device whereby the tension of the restoring spring is regulated. Figs. 4, 5 and 6 are sectional views of the controlling shaft in different positions. Fig. 7 is a sectional view illustrating the arrangements of one of the stop devices whereby movement of the rocker carrying the escapement pawls is limited.

The hanger or support 1 is constructed substantially as described in my companion application, having bearings for an escapement shaft 2 to one end of which a pinion 3 is attached and arranged for engagement with the rack on the paper carriage in the well understood manner. The opposite end of the shaft 3 supports a housing 4 and the escapement wheel 5, the latter being mounted loosely on the shaft and interlocked with the housing 4 against rotation in one direction. The lower portion of the hanger 1

carries a rocker 6, to which is pivoted a pawl 7 actuated in one direction by spring 8 and whose movement in that direction is limited by an offset 9 on the rocker. A pawl 10 is also carried by the rocker 6, and may be moved and locked at either side of the pawl 7 as required to adjust the two pawls for regular or speed escapement as desired and as fully described in my companion application above referred to. The pawl 10 is pivotally supported and may be adjusted and held at either side of the pawl 7. A locking pin 10^a is movably mounted in a hole in an arm on the rocker 6 and may be withdrawn so as to permit adjustment of the pawl 10 from one position to another. The pin 10^a extends against the side of the pawl 10 effectively to lock or hold said pawl in either adjustment, whether for speed or regular escapement. By oscillation of the rocker 6 the pawls 7 and 10 are moved alternately into engagement with the wheel 5, thereby permitting the shaft 2 to rotate intermittently and the paper carriage controlled thereby to move laterally. Movement of the rocker 6 in one direction is effected through the medium of well known connections leading to an arm 11 on the rocker, and movement in the opposite direction is effected by a spring 12, the latter also serving to hold the rocker in its idle or rest position.

A shaft 13 is supported in bearings on the hanger 1, and is provided near its lower end with a plane surface 14. At the lower end of the hanger 1 an abutment or stop pin 15 is carried and held against the shaft 13 by a spring 16. Said pin is in position to be engaged by a projection 17 on the rocker when the latter is oscillated by downward movement of the arm 11, and thereby to stop further movement of the rocker. Above the rocker support a pin 18 is supported in a manner similar to the pin 15, and is arranged as a stop and abutment for the rocker in its idle or rest position. Opposite the end of the pin 18 on the shaft 13 a plane surface 19 is formed at right angles to the plane surface 14, and a plane surface 20 is formed on the shaft on the side opposite from said surface 14. A thumb nut 21 on the upper end of the shaft 13 and above the machine, affords means for rotation of the shaft as required to adjust the escapement for regular or speed escapement. A

pointer 22 attached to the shaft indicates in which adjustment the escapement is located.

Adjustment of the pawls 7 and 10 for regular and speed escapement is effected in the same manner as described in my companion application above referred to. By turning the shaft 13 until the plane surface 19 is opposite the pin 18, the pawl 10 having been previously adjusted, speed escapement will be effected. The spring 12 will draw the rocker 6 to hold the pawl 10 in engagement with the escapement wheel, and during the downward movement of the arm 11 said pawl 10 will move out of engagement with the wheel, and put the pawl 7 in position to be engaged by the advancing tooth on the wheel. In the adjustment shown in the drawing, which is for regular escapement, the shaft 13 presents a round surface to the pin 18 and holds the pawl 7 in engagement with the escapement wheel so that on downward movement of the arm 11 the pawl 7 is swung out of engagement with the escapement wheel and the pawl 10 prevents operation of the escapement until return movement takes place. Adjustment of the shaft 13 to present the plane surface 19 to the pin 18 also presents the round surface of the shaft to the pin 15, so that the rocker 6 moves thereon the same distance at each operation, whether adjusted for regular or speed escapement.

One end of the spring 12 is attached to the lower arm of the bell crank lever 23 pivoted to the under side of the hanger or support 1. A bell crank lever 24 is pivoted beside the lever 23 and has an arm 25 extending under the upper arm of said lever 23, and an extension 26 bearing against the shaft 13. When the shaft 13 is adjusted to present a round surface to the pin 18, the extension 26 rests against the plane surface 20. When, however, the shaft 13 is turned to bring the plane surface 19 against the pin 18, a round surface of the shaft is presented against the extension 26 as will be obvious by reference to Fig. 4, thereby holding the tension of the spring 12 constant or unchanged so that the rocker 6 will be under the same tension at all times, except when voluntarily changed. A screw 27 operates through the upper arm of the lever 23 and against the arm 25 of the lever 24, so that by operation of said screw the two levers may be adjusted with respect to each other. By moving the lower arm of the lever 23 in one direction the spring 12 will be extended and its tension increased, and by moving it in the opposite direction it will be relaxed. The screw 27 projects through a hole 28 in the upper portion of the hanger 1, affording means for regulating the tension of the spring 12 from the top of the machine.

I am aware that there may be modifica-

tions and alterations in the construction and arrangement of the parts embodying this invention without departure from the spirit and scope of the invention, and I do not restrict myself to identical features of construction or arrangement, but

What I claim and desire to secure by Letters Patent is:

1. In an escapement mechanism, the combination with a pawl carrier, and pawls carried thereby, and means for adjusting said pawls for regular or speed escapement as desired, of stops for said pawl carrier, and a single element for adjusting said stops to correspond with the adjustment of the pawls, substantially as specified. 75

2. In an escapement mechanism, the combination with a pawl carrier, pawls carried thereby, and means for adjusting said pawls for regular or speed escapement as desired, of stops for limiting the movement of the pawl carrier in both directions, and a single element operable to adjust said stops to correspond with the adjustment of the pawls, substantially as specified. 85

3. In an escapement mechanism, the combination with a pawl carrier, pawls carried thereby and means for adjusting said pawls for speed or regular escapement as desired, of independently movable stops for limiting the movement of said pawl carriers in both directions, and an operating element for adjusting said stops to correspond with the adjustment of the pawls for speed or regular escapement, substantially as specified. 95

4. In an escapement, the combination of a pawl carrier, pawls carried thereby, and means for adjusting said pawls for regular or speed escapement as desired, of independently movable stops arranged in the path of movement of the pawl carriers to limit the movement of said carrier in both directions, and a manually operable device for adjusting both the said stops at one operation, substantially as specified. 100

5. In an escapement, the combination with pawl carrier, pawls carried thereby, and means for adjusting said pawls for speed or regular escapement as desired, of independently movable stops arranged to limit movement of the pawl carrier, in both directions, manually operable means to adjust both of said stops at a single operation, and an indicator controlled by said means indicating the adjustment of the escapement, substantially as specified. 115

6. In an escapement, the combination with a pawl carrier, and the escapement pawls carried thereby, of stops limiting movement of the pawl carrier in both directions, and a single element operable to adjust all of said stops in different relative positions. 125

7. In an escapement, the combination with a pawl carrier, and the escapement pawls carried thereby of independently movable

- stops for limiting movement of the pawl carrier in both directions, and manually operable means for adjusting all of said stops in different positions at a single operation, substantially as specified.
8. In an escapement mechanism, the combination with a pawl carrier, and the escapement pawls carried thereby, of stops limiting movement of the pawl carrier, a spring actuating the carrier in one direction, and a single element for adjusting said stops in different positions and holding the spring at substantially the same tension.
9. In an escapement mechanism, the combination with a pawl carrier and the escapement pawls carried thereby, of stops limiting the movement of the pawl carrier in both directions, a spring actuating the pawl carrier in one direction, and an element operable to change the position of said stops and hold the spring at substantially uniform tension, substantially as specified.

10. In an escapement, the combination with a pawl carrier, of stops limiting movement of said carrier in both directions, and means for adjusting all of said stops in different positions at a single operation as required for speed and regular escapement.

11. In an escapement, the combination with a pawl carrier, of stops limiting movement of said pawl carrier in both directions, a device operable to adjust said stops in different positions, a spring actuating said pawl carrier, and means operated by said device effectively to regulate the tension of said spring, substantially as specified.

In testimony whereof, I hereunto affix my signature to this specification this 13th day of January, 1909, in the presence of two witnesses.

JOSEPH RABER. [I.S.]
